(57) CLAIM

The ornamental design for a computer generated icon for a display or screen, as shown and described.

DESCRIPTION

FIG. 1 is a front view of a first embodiment of a computer generated icon for a display or screen showing my new design, wherein said icon includes a plurality of sets of indicia which vary sequentially in display size, and wherein at least one of said sets of indicia is centrally located and is the largest in size;

FIG. 2 is a front view of a second embodiment of a computer generated icon for display or screen showing my new design, wherein said icon includes a plurality of sets of indicia which vary sequentially in display size, and wherein at least one of said sets of indicia is centrally located and is the largest in size;

FIG. 3 is a front view of a third embodiment of a computer generated icon for display or screen showing my new design, wherein said icon includes a plurality of sets of indicia which vary sequentially in display size, and wherein at least one of said sets of indicia is centrally located and is the largest in size;

FIG. 4 is a fourth embodiment of a computer generated icon for display or screen showing my new design, wherein said icon includes a plurality of sets of indicia which vary sequentially in display size, and wherein at least one of said sets of indicia is centrally located and is the largest in size;

FIG. 5 is a fifth embodiment of a computer generated icon for display or screen showing my new design, wherein said icon includes a plurality of sets of indicia which vary sequentially in display size, and wherein at least one of said sets of indicia is centrally located and is the largest in size;

FIG. 6 is a sixth embodiment of a computer generated icon for display or screen showing my new design, wherein said icon includes a plurality of sets of indicia which vary sequentially in display size, and wherein at least one of said sets of indicia is centrally located and is the largest in size.

The broken line disclosure of a display or screen in all views, the interior rectangle in FIGS. 1, 4 and 6 and the broken line drawing of letters in all views are for illustrative purposes only and form no part of the claimed design.
